UNITED STATES PATENT OFFICE.

WILLIAM F. BROOK, OF PHILADELPHIA, PENNSYLVANIA, ASSIGNOR TO
TETLOW & BROADFIELD, OF SAME PLACE.

MACHINE FOR FOLDING CLOTH.

SPECIFICATION forming part of Letters Patent No. 413,019, dated October 15, 1889.

Application filed April 20, 1887. Serial No. 235,505. (No model.)

To all whom it may concern:

Be it known that I, WILLIAM F. BROOK, a citizen of the United States, residing in the city and county of Philadelphia, State of Pennsylvania, have invented a new and useful Improvement in Machines for Folding Cloth and other Fabrics, which improvement is fully set forth in the following specification and accompanying drawings.

10 My invention relates to improvements in machines for folding cloth; and it consists in a novel form of apparatus for this purpose. It will be fully described in the following specification, and the features which I consider novel with me will be particularly pointed out in the claims which follow this specification.

Figure 1 is a side elevation of my improved cloth-folding machine. Fig. 2 is a plan view 20 of the same.

Similar letters of reference indicate corresponding parts in the two figures.

Referring now to the drawings, A represents the frame of the machine, in which is 25 journaled the shaft C, having mounted thereon at one end the pulley B, which is connected to the driving-power. On the shaft C is a pinion c, gearing with a pinion c' on a shaft C³, and meshing with a pinion on the 30 shaft C⁴, whereby motion is communicated from the said shaft C to the cross-shafts C³ C⁴, which are parallel with the shaft C. The shaft C³ serves to drive the rolls of the cloth-feeding carriage and the shaft C⁴ of the carriage, as will be hereinafter explained.

F is a shaft journaled in supports affixed to the side of the frame and having at its left-hand end the bevel gear-wheels E E, which mesh with a similar bevel-wheel D on the 40 shaft C⁴, above referred to. These bevel-wheels E E are affixed each to a loose sleeve E², so as to normally run freely on the shaft F without giving to it any rotation.

D' is a sliding clutch member splined on 45 shaft F, and provided with a pivoted handle H', having fixed bearings on a shifting-rod M', adapted to throw the clutch member D' into connection, as desired, with either cog-wheel for changing the direction of motion of the shaft in a manner well understood, the clutch member being provided with ratchet-teeth on the opposite sides thereof, as shown.

At the right-hand end of shaft F is located a bevel-gear G, which meshes with a similar bevel H on a cross-shaft C' parallel to shaft 55 C. These two pieces of shafting have pulleys I I', around which passes a chain belt K, connected to a carriage N at a point L, as shown. This carriage N is supported on rails R⁸ R⁹ by wheels O O' O² O³, and carries the cloth 60 guiding and folding rolls R⁵ R⁶ R⁷ R', the latter located at the lower ends of arms S, as clearly shown in Fig. 1.

M² is an extended bearing attached to the car and adapted to slide on the rod M' and 65 be brought alternately into contact with shifting-blocks a a', affixed to the sliding shifting rod M', and having buffer-springs b b', as shown. This constitutes all of the mechanism for driving the carriage.

I will now describe the cloth-feeding portion of the machine: On the rear or outer end of the shaft C³ is located a bevel gear-wheel w², which meshes with a similar wheel w³, splined on the feathered shaft F', which latter 75 is journaled to the frame A at D' D², and has a feathered bevel-pinion w', with a bearing fixed to the car N.

w is a bevel-pinion on the lower roll R⁵ and meshing with w'. These pinions give motion 80 to the feed-rolls R⁵, and also to the lower feed-roll R⁷, through the agency of a belt B².

R R' R² R³ R⁴ R⁵ R⁶ R⁷ are cloth guiding and feeding rolls, and B' is a belt for driving R².

Having thus described the essential parts of my improved cloth-folding machine, I will now describe its mode of operation.

The cloth to be folded is located on a shaft (not shown) to the left of the roller R, and is 90 passed over R, under R', thence to roller R², driven by belt B', under roller R³, to roller R⁴, between the feed-rolls R⁵ R⁶, and finally down to the last rolls R⁶ R⁷, whence it is fed to the table or place upon which it is desired to fold 95 it. When the machine is started, by giving to pulley B motion in the direction of the arrow, Fig. 1, and the lever H' is so set as to unite the clutch member D to the adjacent clutch member of the left-hand bevel-wheel E, 100 the cloth is fed forward and the carriage N is caused, through the agency of shafting F and C' and the bevel-gears G and H, to be carried to the right until the bearing M², sliding on

rod M' , strikes the buffer-spring b and stop a , and thereby drives said rod to the right, so as to shift the lever H' and cause the clutch member D' to change its position, thus shifting it from the left-hand clutch member to that upon the right, so as to unite it with the other bevel-gear and reverse the motion. The carriage now moves to the left until the sliding bearing M^2 comes into contact with the left-hand buffer-spring b' and stop a' , and again reverses the direction of the shaft F . It will be seen that this oscillating motion causes the chain belt to change the direction successively, so as to reverse the direction of the carriage and carry the cloth C^2 back and forth, so that it is laid in folds, as shown at $z z$, Fig. 1. The cloth is constantly fed forward by the action of the rollers R^2 , R^3 , R^5 , R^6 , and R^7 , the said rollers R^5 , R^6 , and R^7 being actuated by the pulley B on the driving-shaft, which latter, through its pinion c , meshing with the pinion c' of the shaft C^3 , causes the bevel-wheel w^2 to operate the bevel-wheel w^3 , and thereby the shaft F' and bevel-wheels w' and w , and consequently the rollers R^5 , and, by means of the belt B^2 , the rollers R^6 and R^7 . The rollers R^2 , R^3 are operated by means of the belt B' , connecting the roller R^2 and a pulley on the shaft C^3 .

30 Having thus described my invention, what I claim as new, and desire to secure by Letters Patent, is—

1. A cloth-folding device having a carriage with feed-rollers thereon, feeding-rollers independent of said carriage feed-rollers, a driving-shaft, mechanism, substantially as described, connected to said driving-shaft, and consisting of shafts, a belt, and pinions, for operating the feed-rollers on said carriage, and mechanism, substantially as described, consisting of belts and pulleys connected to the driving-shaft for operating said independent rollers, substantially as and for the purpose set forth.

45 2. A cloth-folding machine having a driving-shaft, a shaft connected to said driving-shaft by intermediate gearing and having a bevel-wheel thereon, a counter-shaft with a clutch member splined thereon, and sleeves 50 with bevel-wheels loosely mounted thereon, a tripping mechanism for said member, the shaft C' having a bevel-wheel meshing with a fixed bevel-wheel on the counter-shaft, pulleys on the first-mentioned shaft and the shaft C' , a chain on said pulleys, and a carriage connected to said chain and provided with feed-rolls, said parts being combined substantially as and for the purpose set forth.

60 3. In a cloth-folding machine, a carriage with feeding-rollers thereon, in combination with rollers independent of said carriage feeding-rollers, a driving-shaft, mechanism, substantially as described, connected to the said driving-shaft for operating said carriage 65 feed-rollers and said independent rollers, a belt or chain for moving said carriage, shafting for imparting motion to said belt, and

shifting devices for changing the direction of the movements of said belt or chain at the end of the folds, substantially as described. 70

4. In a cloth-folding machine, a series of feed-rollers with a driving-shaft, gearing, and belt, for giving to the cloth a constant feed, a carriage with cloth guiding and feeding rollers and an extended bearing thereon, mechanism, substantially as described, connected with the shaft of one of said rollers for rotating the same, and a belt connecting said roller with one of the other rollers, a shaft parallel with the driving-shaft and connected therewith by gearing and carrying the bevel-wheel D , a shaft having a chain-connection with the carriage and carrying a bevel-wheel, a shaft having on one end a bevel-wheel gearing with the last previously-mentioned 85 bevel-wheel and on the other end two loose cog-wheels, a clutch member splined on said last-mentioned shaft between said loose wheels, a sliding rod with blocks thereon, and a pivoted handle having fixed bearings 90 on said sliding rod and carrying the intermediate clutch member, said parts being combined substantially as described.

5. In a cloth-folding machine, the frame A , in combination with the shaft C , having driving-pulley B thereon, the cross-shaft C^3 , having a pinion meshing with a pinion on the shaft C , and a bevel-wheel w^2 thereon, the shaft F' , operated by the shaft C and having the bevel-wheel w^3 and the feathered 100 bevel-wheel w' , the carriage N , having a bearing for said wheel w' , the roller R^5 , having wheel w , gearing with bevel-gear w' , and arms S , having rollers R^6 , R^7 , and the belt B^2 , substantially as and for the purpose set forth. 105

6. In a cloth-folding machine, the frame A , in combination with shaft C , with driving-pulley B thereon, the shafts C^3 and C^4 , with connecting-gearing, the bevel-wheel D on shaft C^4 , the shaft F , with loose bevel-gearing E , E' and clutch member D' , and fast bevel-gear G , the shaft C' , with bevel-wheel H , the pulleys I , I' on shafts C^4 and C' , respectively, the chain K , and the carriage N , secured to said chain, substantially as described. 115

7. In a cloth-folding machine, the frame A , in combination with the driving-shaft C , having pinion c , the shaft C^3 , having pinion c' , and shaft C^4 , operated by the shaft C , the bevel-wheel D on said shaft C^4 , the shaft F , with bevel-wheels E , E' , loosely mounted thereon, and the fixed bevel-wheel G thereon, the shaft C' , with bevel-wheel H , meshing with bevel-wheel G , pulleys I , I' on shafts C^4 125 and C' , respectively, the chain K , and carriage N , secured thereto, the bearing M^2 , the rod M' , having spring-buffers b , b' and stops a , a' , and the clutch member D' , with handle, substantially as described.
